US00D651101S

(12) **United States Design Patent**
Ziganek et al.

(10) **Patent No.:** US D651,101 S
(45) **Date of Patent:** ** Dec. 27, 2011

(54) **YARN TESTING APPARATUS**

(75) Inventors: **Norbert Ziganek**, Gutenwil (CH);
Martin Kuster, Eschenbach (CH)

(73) Assignee: **Uster Technologies AG**, Uster (CH)

(**) Term: **14 Years**

(21) Appl. No.: **29/380,276**

(22) Filed: **Dec. 2, 2010**

(51) **LOC (9) Cl.** 10-04

(52) **U.S. Cl.** **D10/46**

(58) **Field of Classification Search** D10/46;

UNITED STATES PATENT AND TRADEMARK OFFICE
CERTIFICATE OF CORRECTION

PATENT NO. : D651,101 S
APPLICATION NO. : 29/380276
DATED : December 27, 2011
INVENTOR(S) : Norbert Ziganek et al.

Page 1 of 1

It is certified that error appears in the above-identified patent and that said Letters Patent is hereby corrected as shown below:

On the Title Page

The foreign priority claim is missing from the title page. It should read,

Item --(30) Foreign Application Priority Data
June 9, 2010 (CH) 137120--

Signed and Sealed this
Fourteenth Day of February, 2012

David J. Kappos
Director of the United States Patent and Trademark Office

UNITED STATES PATENT AND TRADEMARK OFFICE
CERTIFICATE OF CORRECTION

PATENT NO. : D651,101 S
APPLICATION NO. : 29/380276
DATED : December 27, 2011
INVENTOR(S) : Norbert Ziganek et al.

Page 1 of 1

It is certified that error appears in the above-identified patent and that said Letters Patent is hereby corrected as shown below:

This certificate supersedes the Certificate of Correction issued February 14, 2012. The Certificate is vacated since claim to priority was never perfected due to certified copies of the priority documents were never received. Therefore, the Certificate of Correction was published in error and should not have issued.

Signed and Sealed this
Twenty-first Day of May, 2013

Teresa Stanek Rea
Acting Director of the United States Patent and Trademark Office
